UNITED STATES PATENT OFFICE

2,584,644

MOP AND BROOM BRACKET SUPPORT

Carlo Joseph Verdi, Brooklyn, N. Y.

Application September 1, 1950, Serial No. 182,831

2 Claims. (Cl. 211—66)

1
This invention relates to a new and improved broom and mop bracket support.

Its principal object is to provide a broom and mop bracket support, having simple releasable means for securely holding the handles thereof in depending position thereon.

Another object of the invention is to provide a broom and mop bracket support, having means to space the lower part of the broom or mop away from the wall or door on which the bracket is mounted, so that the mop or broom is held in proper vertical position.

Another object of the invention is to provide a broom and mop bracket support which is simple to set up and install, and which can efficiently support any desired number of brooms, mops, or other similar articles thereon.

Still another object of the invention is to provide a bracket support unit for brooms, mops, etc. which can be conveniently attached on a wall, door, or any other desired surface, the unit being neat in appearance.

Other objects of the invention will be apparent from the following description and drawing, which describe and illustrate a preferred embodiment thereof.

In the drawing:

Fig. 1 is a front perspective view of the device, in attached position; and

Fig. 2 is a sectional view on the line 2—2 of Fig. 1, the device being shown secured to a wall.

Referring to the drawing, the improved device comprises a pair of spaced end metal brackets 10; the upper rod or bar 11; the lower spacing bar 12; and the holding members 13 swingably mounted on upper bar 11.

Brackets 10 are complementary in every respect. Each has a vertical upper portion 10a, and a depending forwardly extending lower angular portion 10b. Such angular disposition of said lower portions 10b with respect to their respective integral upper vertical portions 10a is clearly shown in both figures of the drawing. Each upper portion 10a of each said bracket 10 is provided with two or more holes 14 for the reception of screws 15 for attaching or mounting the device on a wall, door, or other surface.

The upper end of each bracket 10 is inwardly turned to form the circular socket 16 for receiving and frictionally engaging the ends of upper bar 11. Similarly, the lower forwardly projecting end of each said bracket is inwardly turned to form the circular socket 17 for receiving and frictionally engaging the ends of lower bar 12.

As shown in Fig. 1, turnably mounted on up-

2
per rod 11 are the holding members 13 and 13a. The said holding members perform precisely the same function, but differ in the manner in which they are formed. Holding members 13 are made from flat pieces of metal, whereas holding members 13a are made from wire.

Each holding member 13 is formed with an opening 18 adjacent its forward end, the function of which will be hereinafter described. The opposite end 19 of each said holding member is loosely coiled or ringed about upper rod 11, so that each said holding member is turnable on said rod and also laterally movable thereon.

Each holding member 13a is made from a single piece of wire, bent to form the depending ring 20, the other end 21 thereof being loosely looped about upper rod 11, the said holding member also having an intermediate vertical shank portion 22. Similarly to holding member 13, holding members 13a are freely turnable or swingable about upper rod 11 from which they depend, and are also laterally movable thereon. Rings or loops 20 of said holding members 13a perform precisely the same function as corresponding openings 18 of holding members 13.

The sectional view of Fig. 2 shows the device mounted on a wall W. In the non-holding position, the locking members 13 and 13a depend vertically and are parallel to the wall, door or surface on which the unit is mounted. In locking position, the said holding members are angularly disposed with respect to the said wall.

Reference is made to Fig. 2 of the drawing for the explanation of inserting and locking the handle H of a mop or broom on the device. The insertion position of said handle in the said locking member is shown in broken lines in the said figure. In such instance, the locking member is turned or swung upwardly until it is in a position perpendicular to wall W and the vertical portions 10a of brackets 10. The upper end of handle H is then inserted upwardly through the bottom of hole 18 of holding member 13. The said holding member will then be caused to move downwardly from the horizontal insertion position (broken lines—Fig. 1) to the angular position (full lines—Figs. 1 and 2) by the downward pull of the mop or broom, until the handle thereof abuts lower bar 12. The said bar, in addition to acting as a spacing member, also serves as a partial stop. The mop or broom is securely held on the device in depending vertical position. To release the broom or mop, it is merely necessary to raise the handle H upwardly, thereby raising holding member 13 to a horizontal position, and

then pulling the upper projecting part of said handle downwardly through the bottom of hole 18 of said holding member.

As indicated in Fig. 2, the bar 12 being spaced from the wall W additionally permits such bar to be used as a support for brushes or other articles by hooking them over the bar.

There has been illustrated and described a preferred embodiment of the invention. It is not desired to be limited to any specific size of device, nor to any specific material from which the parts thereof can be made.

What is claimed is:

1. A wall supported mop and broom holder comprising a pair of spaced end brackets, each said bracket having a depending forwardly extending lower angular portion, a supporting rod carried by the upper ends of said brackets adjacent the wall, a spacing rod carried by the lower angular portions of said brackets and spaced from the wall, said spacing rod being located below said upper supporting rod and anteriorly of the same, holding members swingably mounted on the supporting rod, each of said holding members having a handle receiving opening formed

adjacent the free depending end thereof, each of said holding members being swingable from a handle insertion position to a locking position when said handle abuts the spacing rod.

2. A holder for mops, brooms, and the like in accordance with claim 1, in which the upper and lower ends of each bracket are provided with integral sockets, the said sockets receiving and frictionally engaging the ends of the supporting and spacing rods.

CARLO JOSEPH VERDI.
